CLAIM

An ornamental design for a plate compactor as shown and described.

DESCRIPTION

FIG. 1 is a front perspective view of a plate compactor showing our new design.

FIG. 2 is a right side view thereof.

FIG. 3 is a left side view thereof.

FIG. 4 is a rear view thereof.

FIG. 5 is a bottom view thereof.

FIG. 6 is a front view thereof; and,

FIG. 7 is a top view thereof.

The broken lines shown are for the purposes of illustrating the environment of the article only and form no part of the claimed design.
